VALVE FOR INTERNAL-COMBUSTION ENGINES AND METHOD OF MAKING THE SAME.

1,295,979.

Specification of Letters Patent.

Patented Mar. 4, 1919.

Application filed August 4, 1916. Serial No. 113,191.

To all whom it may concern:

Be it known that we, JOHN H. GOULD and MAX E. KONIGSLOW, citizens of the United States, residing at Detroit, in the county of

5 Wayne and State of Michigan, and at Cleveland, in the county of Cuyahoga and State of Ohio, respectively, have invented a new and useful Improvement in Valves for Internal-Combustion Engines and Methods of
10 Making the Same, of which the following is a specification.

This invention relates to valves for internal combustion engines and the method of making the same.

15 For the correct operation of an internal combustion motor, it is required of the valves that they shall not pit, corrode or go out of round. The valve must operate against a spring tension equal to the maximum

20 vacuum multiplied by the number of square inches of valve area plus the maximum inertia at high speeds. This in some cases is quite heavy and at lower and intermediate speeds when the inertia effect be-

25 comes lessened, forces the valve against its seat with the effect of a hammer-like blow. The valve is subjected to high temperature and in extreme cases must operate after it has reached a temperature beyond the tem-

30 pering point of ordinary carbon steel. Hot gases are blown over it while at this temperature. This may occur at times in the presence of oxygen, or the gases themselves may contain properties injurious to metal, which

35 would be especially susceptible under the influence of heat. This has a tendency to pit, corrode and warp the valve.

In order to overcome these objections, valves have been made of steel alloys which are dense and have a high tempering point.

40 These steels are expensive and, because of their high tempering points and density, are hard to work. The raw material itself is comparatively expensive and on account of

45 the labor required in manufacturing the valves by the methods heretofore employed, the cost of the finished valves is so excessive as to be prohibitive except for use in a few of the higher priced motors. This is espe-

50 cially true of valves in which the valve head and stem are forged or machined from a single piece of stock.

The object of this invention is to produce a light, strong and durable valve for internal combustion engines which is so constructed that the valve head or valve proper will be of uniform density throughout and will not pit, corrode or warp or go out of round, and can be made with the minimum waste and labor from the minimum amount 55 of material, thus making it commercially possible to use the materials best adapted for the purpose and enabling the use of the valves in moderate priced motors.

With this end in view the valve head or 60 valve proper, which is made separate from the stem, is stamped from a flat disk or sheet of a steel alloy having the requisite density and high tempering point. This head is then secured, as by welding, to the valve 65 stem, which can be made of ordinary carbon steel or other suitable inexpensive metal.

By stamping the valve heads from sheet material, as distinguished from forging and machining them to shape, there is very lit- 70

tle waste of material and only a small amount proportionally of the expensive metal is used. The metal of the stamped head is very dense and of substantially uniform character throughout, since the rolled 75

sheet material from which it is made is dense and the density is increased by the stamping operation. In stamping metal and especially when the metal is drawn slightly in the stamping operation, a permanent set in the metal is obtained wherever a pronounced bend is made. In the case of a 80

valve this tends to prevent it from warping or going out of round. The stamped head is of substantially uniform thickness 85

throughout and owing to its greater density and rigidity it can be made thin and light. This is desirable as it reduces the inertia effect, which is especially noticeable at high 90

speeds. It means less work on the cams, 95 push-rods and push-rod guides, and lighter valve springs with less of the hammer-like action when the valve seats, and less noise in the operation of the engine.

The valve heads can be stamped to different shapes suitable for either inlet or exhaust valves and they can be secured to either solid or hollow valve stems in various 100 different ways.

In the accompanying drawings, several different embodiments of the invention are shown.

Figure 1 is a side elevation partly in section showing an inlet valve before the head is welded on the stem.

Fig. 2 is a plan view thereof.

Fig. 3 is a fragmentary elevation, partly in section, showing the completed valve.

10 Fig. 4 is a plan view of the completed valve.

Fig. 5 is a view similar to Fig. 3, showing a slight modification of the valve shown in Fig. 3.

15 Figs. 6 and 7 are similar views showing exhaust valves of two slightly different constructions.

Fig. 8 is a similar view of an inlet valve of another construction.

20 Fig. 9 is a fragmentary sectional elevation of an inlet valve having a hollow stem.

Fig. 10 is a sectional elevation of a hollow stem valve of different construction.

25 Fig. 11 is a fragmentary sectional elevation of still another construction of hollow stem valve.

Referring first to Figs. 1 to 4, A represents the valve head and B the valve stem. The valve head is stamped into shape from 30 a flat metal sheet or disk and as clearly shown in Fig. 1, the head is of substantially uniform thickness throughout and is preferably of shallow, bell-like formation, being hollow and having an upwardly projecting 35 circular marginal flange a. a' is the conical seating face of the valve. The flange extends at an angle to the adjacent portion of the head and in bending the flange and concavo-convex central portion of the head 40 in the stamping operation, the metal is drawn slightly which gives the same a permanent set at the bends with the result that the head, although its walls are thin and of substantially uniform thickness throughout, 45 is very stiff or rigid. The valve head is secured on the stem in this construction by reducing the end of the stem as shown at b in Fig. 1 and passing this reduced end of the stem through a central opening 50 in the valve head. The reduced end of the stem is then swaged to fill the central portion of the cavity of the head and form a central boss or convex portion b' shown in Figs. 3 and 4. The meeting surfaces of the valve head and swaged end of 55 the stem are welded together at c and c' to permanently connect them.

In the construction shown in Fig. 5, the valve head A' and stem B' are substantially 60 the same as above described and the head is slipped over the reduced end of the stem, but instead of the reduced end of the stem being swaged, a separate-piece boss or filler d is employed which fits around the reduced 65 end of the valve in the cavity of the valve

head. In this construction the boss d is welded to the meeting surfaces of the valve head and stem at e and e' and the reduced central portion of the head is welded to the shoulder on the valve stem at e'.

70 f, Figs. 3, 4 and 5 indicates the usual slot for the engagement of a tool for grinding the valve to its seat.

The inlet valve shown in Fig. 8 has a head A² substantially similar in form to the valve heads in the other constructions described but in this construction the valve head has a flat imperforate central portion g which is welded at g' to the flat end of the valve stem B².

80 In the exhaust valve shown in Fig. 6, the head A³, like the heads of the inlet valves, is stamped from a flat sheet or disk and is of substantially uniform thickness throughout and has a marginal flange a³ which is bent at an angle to the adjoining portion of the head. In this valve the flange extends downwardly instead of upwardly so as to leave the upper surface of the valve head over which the exhaust gases flow, free from 85 shoulders or projections which would tend to obstruct the flow of the gases. a⁴ indicates the conical seating face of this valve.

In the exhaust valve, as in the inlet valve, the head is bent at the juncture of the flange 90 with the main portion of the head, and the walls of the head are also bent at a point inwardly from the flange and these bends give the metal of the head a permanent set which prevents the head from warping. In 95 this valve the end of the stem B² is reduced and welded in a central hole in the valve head.

100 Fig. 7 shows an exhaust valve which is similar to that shown in Fig. 6 except that the valve head A⁴ is welded at b⁴ to an enlarged flattened end on the valve stem B⁴.

Figs. 9, 10 and 11 show inlet valves which are provided with hollow stems to further reduce the weight of the valves. The 110 valve heads in these constructions are substantially like the heads of the other inlet valves, being of bell-like formation and flanged, being stamped from flat metal sheets or disks and having walls of substantially 115 uniform thickness throughout. The valve head can be secured to the hollow valve stem in various ways, three different ways being illustrated in Figs. 9 to 11.

120 In Fig. 9 the valve head A⁵ has a central opening through which the reduced end b⁵ of the hollow valve stem B⁵ passes. This reduced end of the stem is expanded to fill the cavity of the valve head and a plug h closes the upper end of the stem and forms a central boss or filler in the valve head. The valve head, stem and plug h are welded together at their meeting surfaces.

125 In Fig. 10 the upper end of the hollow valve stem B⁶ is closed by a plug b⁶ and the 130

valve head A⁶ has a flat imperforate central portion which is welded at *i* to the flat faced ends of the hollow stem and plug b⁶.

In the construction shown in Fig. 11, the 6 valve head A⁷ is secured on the reduced end of the hollow valve stem B⁷ by expanding the reduced end of the stem to fit the cavity of the head and welding the parts together. In this construction the plug or boss shown 10 in Fig. 9 is omitted.

As shown in Fig. 10, the lower ends of the hollow valve stems can be closed by a suitable plug I adapted to be engaged by the valve actuating device. This plug can 15 be welded or otherwise secured to the valve stem.

We claim as our invention:

1. An exhaust valve for internal combustion engines comprising a head centrally 20 supported upon a separate-piece stem, said head consisting of a metal stamping having a bend therein.

2. An exhaust valve for internal combustion engines comprising a head centrally 25 supported upon and permanently connected with a separate-piece stem, said head consisting of a metal stamping having a bent marginal flange.

3. An exhaust valve for internal combustion 30 engines comprising a head centrally supported upon and permanently connected with a separate-piece stem, said head consisting of a metal stamping and being of substantially uniform thickness throughout.

35 4. An exhaust valve for internal combustion engines comprising a head and a separate-piece stem permanently connected, said head consisting of a hollow metal stamping having substantially parallel inner and outer exposed surfaces.

40 5. An exhaust valve for internal combustion engines comprising a head and a separate-piece stem permanently welded together, said head consisting of a hollow 45 metal stamping having a bend therein and having a central attached portion and a peripheral seat portion.

6. An exhaust valve for internal combus-

tion engines comprising a head and a separate-piece stem permanently welded together, said head consisting of a hollow metal stamping having a central hole in which the stem is welded. 50

7. An exhaust valve for internal combustion engines comprising a head and a separate-piece stem permanently connected, said head consisting of a hollow metal stamping having a bend therein, and said stem being hollow. 55

8. An exhaust valve for internal combustion engines comprising a head and a separate-piece stem, said head consisting of a hollow metal stamping and said stem being tubular and welded in a central hole in said head. 60

9. The herein described method of making exhaust valves for internal combustion engines which comprises forming a hollow valve head having a bend therein by stamping the said valve head from a sheet of 65 metal and welding said head onto a stem. 70

10. The method of making exhaust valves for internal combustion engines which comprises forming by stamping a hollow head having a bent marginal flange and welding 75 said head onto a stem.

11. The method of making exhaust valves for internal combustion engines which comprises forming a hollow head of substantially uniform thickness having a bend 80 therein, by stamping the said head from a sheet of metal and welding the head onto a stem.
